UNITED STATES PATENT OFFICE

2,611,521

CARRIER FOR CHIMED CANS

Frank W. Hackman, Maywood, and William J. Poole, Evanston, Ill., assignors to Container Corporation of America, Chicago, Ill., a corporation of Delaware

Application September 16, 1949, Serial No. 116,043

1 Claim. (Cl. 224—45)

1

The present invention relates to improvements in carriers or holders for cans of the type that have recessed or chime type ends, the carrier being adapted to retain the cans by the use of inwardly foldable flaps in a position in which portions of certain of the cans extend out beyond the confines of the carrier. The invention relates particularly to a carrier of this type in combination with an improved construction of inwardly extending flaps for retention of the cans in place within the carrier.

It has been found that certain cans in production runs have end closures that are not uniform in contour. That is, the central portions of the end closures, when the cans are filled, have somewhat of an outward bulge. This is frequently true with canned beer. When a bulge is present in an end can in a row, which is the can that is to be retained in the carrier by engagement of its inner chime portion by an inwardly extending retaining flap, such a can is frequently not securely held because the crest of the bulge contacts the retaining flap at a distance from its free edge and causes the extremity of the flap to contact very close to the outer edge portion of the chime which will tend in some cases to cause the flap to slip out of positive engagement with the chime and allow the can to slip from the carrier.

Another disadvantage found to exist with regard to certain retaining flaps is that, when three or more cans are to be placed in a row, the trailing edge of the chime of the middle can or cans will catch on the outer portion of the inwardly folded retaining flap instead of moving to the interior part of the carrier and must be extricated with care from engagement with the outer or hinge edge of the infolded flap and with consequent slowing up the operation of packing the carrier.

An object of the present invention is to provide a retaining flap construction in combination with a carrier or holder for cans which will cause cans to be held securely in the carrier by an inwardly extending retaining flap even though the can end closures have bulging portions. Another object is to provide a retaining flap construction in combination with the structure of the carrier or holder which will allow the chime portion of a can to pass easily over the inwardly extending retaining flap and into the interior of the carrier without likelihood of the trailing edge of the chime catching on the outer portion of the inturned retaining flap at the place where the retaining flap is hingedly connected to the carrier. Other objects of the invention are generally to

improve carriers or holders of this type and to reduce the cost of manufacture by reducing the size of the retaining flaps while at the same time making them more efficient for their intended purposes.

Other objects will appear in the following description and will be pointed out in the claim.

In the drawings:

Fig. 1 is a perspective view of a can carrier 10 having in combination therewith a plurality of retaining flaps constructed in accordance with the present invention and illustrating in dotted lines a can positioned within the carrier;

Fig. 2 is a fragmentary sectional view taken 15 along line 2—2 of Fig. 5, looking in the direction of the arrows;

Fig. 3 is a fragmentary sectional view taken along line 3—3 of Fig. 2, looking in the direction of the arrows;

Fig. 4 is a fragmentary plan view showing a part 20 of the bottom panel of the carrier together with the inturned flap carried by the bottom panel and illustrating a can beginning to pass over the flap;

Fig. 5 is a view, similar to Fig. 4, illustrating 25 a can which has been moved into the carrier to the point at which the inturned retaining flap snaps upwardly behind the advancing chime of the can to prevent reverse or outward movement of the can;

Fig. 6 is a view similar to Figs. 4 and 5, and 30 illustrates a can on the way to being moved to an inner part of the carrier, the can being illustrated with its chime as it appears after having passed over the hinge edge of the inturned flap;

Fig. 7 is a fragmentary plan view of a prior 35 form of carrier formed with an inturned retaining flap which has substantially the contour of the inner edge of the chime;

Fig. 8 is a fragmentary sectional view taken 40 substantially along the line 8—8 of Fig. 7, looking in the direction of the arrows, and illustrating how the inturned flap shown in Fig. 8 is caused to be bent if the can end closure has a bulge therein; and

Fig. 9 is a fragmentary sectional view taken 45 substantially along the line 9—9 of Fig. 8, looking in the direction of the arrows, and illustrating how the bulged can end closure displaces the extremity of the flap from retaining engagement with the can chime.

The retaining flaps of the carrier of the present invention are preferably formed as integral extensions of the top and bottom walls of the carrier and are provided with laterally spaced chime-engaging portions adapted to contact separated

places of the inner portion of the chime of a can, and formed so as to remain out of contact with that portion of the can chime which is remote from the hinge or base portion of the flap. The retaining flaps also are suitably restricted in width adjacent their hinge portions transversely of the row in the carrier so that the width of the flap along the line of juncture with the bottom wall of the carrier is substantially less than the diameter of the can chime as measured inside the chime.

Referring to the drawings, in Fig. 1, the carrier is shown as comprising a collapsible construction having a foldable bottom indicated generally at 5, side walls 6 and 7 hingedly related to the lateral edges of the bottom, a foldable top wall indicated generally at 8, a central panel 9 extending from the mid-portion of the bottom to the mid-portion of the top and hingedly related to the foldable top and bottom members, and a carrying portion, indicated generally at 10, hingedly related to the foldable top wall and extending upwardly in alignment with the central panel 9.

While the carrier herein disclosed may be formed in various manners it is preferably formed from a single blank of sheet material. The foldable bottom section 5 is formed from the two panels 11 and 12 defined respectively from the side walls 6 and 7 along crease lines 13 and 14. The central panel 9 is hingedly related at its lower edge to the bottom section 12. The bottom section 11 has a flap 19 which is hinged thereto along its outer edge and is suitably secured to the lower edge portion of panel 9.

The carrying section 10 comprises panels 20 and 21 hinged to each other along crease line 22 and hinged to the respective top walls 15 and 16 along crease lines 23 and 24.

The carrying section is formed with openings 26, 26 in the panels 20 and similar openings in the panel 21. The stock of these openings is not cut completely away but is left in the form of tabs hinged to the top edges of the openings. This construction permits the tabs to be swung together to one side or the other to permit a person's fingers to be extended through the openings.

In order to reinforce the carrying section the central panel 9 is made of such length as will cause it to extend to a position between the panels 20 and 21, and panel 9 is preferably formed with openings adapted to register with openings 26, 26.

As described thus far, the carrier is substantially like that disclosed in the pending application of Thomas W. Foster, Serial Number 106,260, filed July 22, 1949, now Patent No. 2,523,985, dated September 26, 1950, for "Carrier for Chimed Cans."

For the purpose of retaining chimed end cans in engagement with the carrier the bottom wall sections 11 and 12 and top wall sections 15 and 16 are preferably formed with integral retaining flaps 34, 34 and 35, 35 respectively at each end of such wall sections. As these retaining flaps are illustrated as being formed alike, a description of one flap with relation to the bottom panel and its retaining function with respect to the bottom of a can will suffice.

Referring to Figs. 1, 4, 5, and 6, the flap 34, extending from the end of bottom panel 12, is generally of transversely elongated, rectangular form and has spaced chime-engaging edge portions 36, 36 which terminate at their inwardly di-

rected ends in an edge portion 37, which preferably is generally parallel to the crease line 38 between the flap 34 and the bottom panel 12. The edge portions 36, 36 may be substantially straight but, as herein illustrated, are slightly curved to conform approximately with portions of the arc of a circle whose center is in line with the middle of the bottom section 12, and approximately on the crease line 38.

Essentially, the edge portion 37 of the flap 34 is so formed as to be substantially free from engagement of that portion of the chime of the can which is located in the innermost position with respect to the carrier.

It will be understood that the pressure of a can against flap 34 in its infolded position will tend to hold it in such infolded position close to the bottom panel 12. The resiliency of the paperboard will cause the flap to have an upward bias forcing it against the end panel of the can, whereby the edges 36, 36 will engage against the inner portion of the chime of the can. By constructing the flap 34 as a comparatively narrow flap measured longitudinally of the bottom panel 12, somewhat less than one-half the width of the bottom panel, it is to be noted that the chime-engaging edge portions 36, 36 are separated so as to engage against relatively widely separated sectors of the chime of a can. The flap will be bent in a direction transversely of the bottom panel 12 if the center portion of the can in the carrier is bulged outwardly of the can so as to cause bending of the central portion of the flap 34. When this is the case the central portion of the flap will be deflected to accommodate the bulge without causing the displacement of the edges 36, 36 from their engaging position with respect to the inner surface of the chime. The natural resiliency of the paperboard tends to keep the opposite end portions of the flap in firm engagement with the end of the can adjacent the chime, and the fact that the mid portion of the flap is deflected, due to a bulge in the mid portion of the can end, does not affect the retaining function of the edges 36, 36. The relationship just described is illustrated in Figs. 1, 2 and 3 wherein a can 45 is shown in engaged relation to the flap 34. The edge portions 36, 36 of the flap are in engagement with portions of the chime 46 and the central portion of the flap 34 is shown as deflected downwardly by the bulged can end 47. The fact that the central portion of the flap 34 is bowed downwardly beyond the plane defined by the edge portions 36, 36 does not influence the engagement of the edges 36, 36 against the chime of the can.

The lateral edge portions of the flaps 34 indicated at 39, 39 are preferably cut so that they will extend from the edge portions 36, 36 back to the edge of the bottom panel 12 along a line located inwardly from the arc of a circle generally defined by the edges 36, 36. In the present instance these lateral edges 39, 39 are illustrated as cut so as to extend outwardly at approximately a right angle to the crease line 38.

With the edges 39, 39 formed as illustrated, a chimed can 45 can be pushed into the open end of the carrier and the trailing edge of the chime 46 will ride smoothly over the flap 34. There will be no point at which such chime engages against the hinge side of the inturned flap in such manner as to cause the chime of the can to catch and be held. The reason for this is that the side edges 39, 39 being disposed inwardly

of a line defining the arc of a circle similar to the interior of the can chime, permit the can to move inwardly of the carrier beyond the line of its greatest diameter before any contact is made by the chime with the edges 39, 39. Thus, when portions of the chime come in contact with the edges 39, the contact will be at such an angle with respect to the chime as to cause the chime to ride upwardly over the edges 39, 39 and catching of the chime against the rear or hinge edge of the flap will be avoided.

By comparison of Figs. 2, 3, and 5 on the one hand and Figs. 7, 8, and 9 on the other hand, the advantages of the present invention may best be appreciated. Figs. 7 to 9 inclusive illustrate an earlier form of the device which has been found to have certain disadvantages, particularly when the carriers are intended for use with a type of canned product such as beer in which bulges in the can ends frequently occur. Figs. 8 and 9 illustrate the bottom portion of a can in the carrier in the position in which it would be retained adequately in the carrier, except for the fact that the can end has a bulge, as indicated. In this prior form, the bottom portion of the carrier is designated at 50, this bottom portion being connected with vertical panel portions 51 and 52 corresponding with panels 7 and 9. The retaining flap is indicated at 53, formed as an integral extension of the bottom 50 and hinged along fold line 54 so as to be foldable inwardly of the carrier to lie adjacent the bottom 50.

In Figs. 7, 8, and 9 the can is indicated at 60 with an end closure 61 and a chime portion 62. The end closure 61 is illustrated as somewhat bulged in Figs. 8 and 9. By reference to Fig. 8 it will appear that the central portion of the flap 53 will be deflected downwardly along a line extending at right angles to the fold line 54. Due to this deflection the central extremity of the flap 53, indicated at 53a in Fig. 9, will be brought to a position in which it is not in engagement with the chime 62. From the end portions of the hinge of the flap 53 to points near the extremity 53a the engagement between the flap and the chime becomes progressively less, there being no engagement between the chime and a portion of the flap at its extremity. Due to this relationship certain movements of the can relative to the carrier, as when a filled carrier is jarred due to striking some stationary object while being carried by the hand, tend to cause the flap 53 to become entirely displaced from holding engagement with the can chime, thus permitting displacement of the bottom of the can with consequent slipping from the carrier.

By shortening the retaining flap and reducing the area of engagement with the chime, as indicated at 34 in Fig. 1, deflection of the flap, due to a bulged can end, will not cause displacement of any portion of the chime engaging edges 36, 36 and such edges will remain in firm engaging relation with the chime of the can.

When it is desired to use the carrier it will be expanded from a collapsed flat form to the form illustrated in Fig. 1. The retaining flaps on the top and bottom walls will be folded inwardly. The carrier is then ready to receive cans. In practice, if three cans are to be inserted in each row, one can will be inserted in each of the compartments of the carrier at one end and two cans will be inserted into each compartment at the other end. Due to the lateral edges of the flaps 34, 34 being offset inwardly from the edges

of the top and bottom panels the chime of the advancing can of the group of two cans to be inserted through one end of each compartment will not tend to catch upon the hinge edge of the inturned retaining flap but will ride smoothly past such hinge edge. When the group of two cans has been moved inwardly of the carrier to its final position the chimes of the trailing can will be engaged by the top and bottom retaining flaps, each snapping into engaging relation to the chime. Even though the central portion of each can end has a bulge, the lateral end portions of the flaps will nevertheless snap into engaging relation to the chimes because the stiffness of the paperboard will cause the lateral edges of the flaps to contact firmly the can end even though the mid portion of the flap is bowed or deflected.

While the four can retaining elements have been illustrated and described as being identical, and are preferably so for economy and convenience of manufacture and loading, it is within the scope of the invention to have certain of the retaining elements, particularly those at the top of the carrier, constructed in a different manner.

While the present description sets forth a preferred embodiment of the invention, certain changes may be made in the construction without departing from the spirit of the invention, and it is therefore desired that the present embodiment be considered in all respects as illustrative and not restrictive, reference being had to the appended claim rather than to the foregoing description to indicate the scope of the invention.

We claim:

35 A paperboard carrier for a row of chimed cans of predetermined height and diameter especially adapted for use with such cans having bulging end closures, said carrier comprising elongated top and bottom panels and vertical side panels 40 connected to the longitudinal edges of the top and bottom panels thereby forming a compartment having an interior height and width substantially the same as the exterior height and diameter of the cans, respectively, and a can retaining flap hinged to the bottom panel adjacent an end thereof foldable along a transverse hinge line inwardly against the bottom panel, said flap having laterally spaced chime-engaging 45 edge portions, said flap having a dimension measured along said transverse hinge line substantially less than the width of the bottom panel and less than the diameter of the inner surface of the can chime, and being disposed symmetrically with respect to the width of the bottom panel to permit traverse of a can thereover inwardly of the compartment with the trailing edge portion of the chime engaging the end edges of the flap at such angles that the can 50 during its inward movement rides smoothly over the flap, and said flap having a dimension measured perpendicular to said transverse hinge line somewhat less than one-half the width of said bottom panel, the laterally spaced edge portions 55 of the flap being adapted to conform to the inner chime surface of a can for engaging spaced sections of the inwardly disposed portion thereof upon disposition of a can having a bulging end closure over the flap with the spaced edges of 60 the flap enclosed by the chime to retain the can against outward movement, the can retaining flap being cut away on both sides from the hinge line to the lateral chime-engaging portions sufficiently to avoid contact with the can chime, and 65 also being cut away beyond the chime engaging 70 75

portions to avoid contact with the can chime, whereby said laterally spaced chime-engaging portions provide the sole points of contact with the can chime.
